UNITED STATES PATENT OFFICE.

THOMAS HENRY BAMFORTH, OF NORTH VANCOUVER, BRITISH COLUMBIA, CANADA,
ASSIGNOR OF ONE-HALF TO RUBY MAE RAWLINGS, OF VANCOUVER, CANADA.

GAME.

1,388,505.

Specification of Letters Patent. Patented Aug. 23, 1921.

Application filed May 13, 1920. Serial No. 381,143.

To all whom it may concern:

Be it known that I, THOMAS HENRY BAMFORTH, a subject of the King of Great Britain, and a resident of North Vancouver, 5 in the Province of British Columbia, Canada, have invented certain new and useful Improvements in Games, of which the following is a specification.

My invention relates to improvements in 10 games, with more particular reference to a game imitative to a certain extent of the operations of corraling cattle and placing them in stock yards and in which the object of each player is to win the game by obtaining 15 the largest number of points each representing one head of stock and obtained by the closing of suitably arranged corrals and stock yards. A further object is to provide a game which is simple, inexpensive, and highly interesting.

I attain these objects in the manner hereinafter described and by the means illustrated in the accompanying drawing in which—

25 Figure 1 is a plan view of the board on which the game is played.

Fig. 2 is a view of a corral bar.

Fig. 3 is a view of a car counter.

1 indicates the board on which the game 30 is played, which board may consist of a square base formed of any suitable material such as stout paper or cardboard, or by printing the game plan on paper or other material, and affixing it to wood or metal 35 base. The board may be of any suitable size and is divided at each side into an even number of outer squares 2; in the plan illustrated there are eight outer squares along each side and these are termed "corrals."

40 Within the large square thus inclosed by the rows of outer squares there are placed at each corner larger squares, 3, 4, 5 and 6, preferably equal in area to four of the outer squares termed "Stock yards," while between 45 these larger squares and contiguous to the outer squares are arranged squares 7 of equal size to the outer ones, also forming "corrals." The space remaining at the center of the board forms a large stock yard 50 and is named the "Union Stock Yard." The value given to the respective "corrals" and "stock yards" are marked in numerals within each of them as shown and to play the game a number of "corral bars" 8 are 55 provided, each of which is equal in length

to one side of a "corral" or to one-half of a side of a small "stock yard," that is to say, it takes four bars to inclose a corral and eight bars to inclose a small stock yard, sixteen bars being required for the large 60 stock yard in the center.

The game is played according to the following rules:

1. The object of the game is to secure the largest number of points. Each point represents one head of stock.

2. Each corral or yard contains the number indicated.

3. Each player, playing in turn, places a bar on any corral he may select.

4. The player putting the last bar on any corral, thereby closing it, calls out "Corral" and tallies the number of points the corral closed calls for.

5. When a corral is closed the car of stock 75 is placed in the Union Stock Yard and these cars remain until the game is ended.

6. The game is ended when the last bar is laid to close the Union Stock Yard.

7. The player succeeding in closing the 80 Union Stock Yard calls out "Union Stock Yard closed," and adds to his score five points for each car in the stock yard.

8. Any player closing two corrals by placing the dividing bar between them calls 85 "Double corral" and tallies the contents of both corrals.

Counters in the shape of small imitation cattle cars are provided for each corral and when a player closes a corral he tallies the 90 value of the corral, at the same time placing a counter in the "Union Stock Yard." All the counters so placed therein remain until the game is ended when they are added to the score of the player closing the yard according to rule 7.

It will be seen that the game is highly interesting as, while the object of each player is to himself place the last bar to close a corral or yard the object of each of the other players 100 is to prevent him from doing so. The game may be made more interesting by marking certain of the corrals with a brand, as indicated at 10, so that a player closing a corral containing branded cattle becomes a 105 rustler and is penalized by the loss of ten points, which are added to the scores of the other players.

It will be seen that I have devised a simple and inexpensive game requiring the exer-

cise of skill to play it and affording great amusement and interest.

What I claim as my invention is:

1. In a game of the character described, 5 a board having a row of small outer squares along each side, larger squares at each corner of the space inclosed by the small squares, small inner squares between the large ones, the remaining space forming a central in- 10 closure bounded by the larger squares and the small inner squares, all of said squares having values, and bars adapted to be placed by the players to inclose the squares whereby the player placing the last inclosing bar 15 on a square scores the value of the square so inclosed.

2. In a game of the character described, a board having a row of small outer squares along each side, larger squares at each corner of the space inclosed by the small squares, small inner squares between the large ones, the remaining space forming a central inclosure bounded by the larger squares and the small inner squares, all the 20 said squares having values, bars adapted to

be placed by the players to inclose the squares whereby the player placing the last inclosing bar on a square scores the value of the square so inclosed, and a counter for each square won by the player closing the 30 square.

3. In a game of the character described, a board having a row of small outer squares along each side, larger squares at each corner of the space inclosed by the small squares, 35 small inner squares between the large ones, the remaining space forming a central inclosure bounded by the larger squares and the small inner squares, all the said squares having values and several of the squares 40 having distinctive brands marked thereon, and bars adapted to be placed by the players to inclose the squares whereby the player placing the last inclosing bar on a square 45 wins or loses the value of the square so inclosed according to whether it is a branded or an unbranded one respectively.

Signed at Vancouver, B. C., Canada, this 29th day of April, 1920.

THOMAS HENRY BAMFORTH.
